UNITED STATES PATENT OFFICE.

STANISLAUS PALMOWSKY, OF NEW YORK, N. Y.

CIGARETTE-TIPPING MACHINE.

No. 909,931.

Specification of Letters Patent.

Patented Jan. 19, 1909.

Application filed April 29, 1908. Serial No. 429,816.

To all whom it may concern:

Be it known that I, STANISLAUS PALMOWSKY, a subject of the Czar of Russia, residing at New York, in the county of New York and State of New York, have invented certain new and useful Improvements in Cigarette-Tipping Machines, of which the following is a specification, reference being had therein to the accompanying drawing.

10 This invention relates to mechanism for providing cigarettes with tips of cork or other suitable material and is designed to quickly turn out finished cigarettes provided with tips of superior finish and appearance.

15 To this end the invention comprises such details of construction and elements of parts as will hereinafter be described in detail, while reference is had to the accompanying drawing in which the invention is shown in 20 its preferred form but as changes may be made within the legitimate and intended scope of the invention and the claims I do not wish to be limited to the structure shown.

25 In the said drawings:—Figure 1 is an elevation of a mechanism for tipping cigarettes embodying my invention, Fig. 2 is a detailed view showing the parts of the mechanism immediately adjacent the cigarette during the tipping operation. Figs. 3 and 4 are diagrams showing the movements of some of 30 the principal parts, Fig. 5 is an end view looking from left to right at Fig. 1, and Fig. 6 is a plan view.

35 Referring to Fig. 1 the reference numeral 25 indicates an endless conveyer suitably supported adjacent to the machine and upon which the cigarettes may be placed in any suitable manner and by any suitable means. From the said conveyer the cigarettes pass 40 on to a drum 26 provided with depressions 38 each of which is adapted to receive a single cigarette as shown and from this drum, which may be rotated from any convenient part of the mechanism not shown, 45 the cigarettes fall singly upon a stationery table or shelf 39 provided with depressions 40 for receiving the same one at a time. On either side of said table 39 I provide carriers 41 which are provided with cavities as shown 50 for receiving the cigarettes and by means of said carriers the cigarettes are progressed along said table. The carriers are slidably mounted upon and joined by a suitable base 41^a having a stem 45 and vertical reciprocating

55 motion is imparted to said stem by means of the lever 43 mounted at 43^a and by cam 33; while a horizontally reciprocating motion is imparted to the carrier by means of link 44 which is pivoted at 44^a and by lever 42 mounted at 42^a, and cam 46 as 60 clearly shown in Fig. 1, the springs 42^b and 43^b keeping the parts in position. The said cams are mounted on a shaft 34 and are driven from the driving shaft 35 by means of gears 37 and 36. By these means the carriers are given an elliptical motion and as they rise and move toward the left the cigarettes are progressed and moved along table 39 to the table 47 from which they are placed 65 upon the member 12 by the hands 132. 70

1 is a base upon which is mounted a bracket 93 in which reciprocates a vertical member, which for the sake of convenience I shall call a seaming member, 150, which is operated by the coaction of its roll 94 axially 75 mounted thereupon and cam 95 on a shaft 79. In front of the bracket two wrapping jaws 96, are provided (see Fig. 3). These jaws are given an inward and upward movement and close the cork around the cigarette 97 80 supported on a member 120, upon which is placed a piece of gummed cork paper 3 (see Fig. 6). Each jaw 96 is carried by a lever 99 to which are pivoted the levers 100 and 101. The lever 100 is pivoted at 102 to the 85 rocking lever 103, which is pivoted at 106 and the rocking lever 103 is rocked by the coaction of its cam roll 104 and the cam 105 and gives the jaw 96 the back and forth motion with respect to the cigarette. The 90 lever 101 is also pivoted at 106 and is moved up and down by the coöperation of its cam roll 107 and the cam 108, the springs 109—109^a keeping the rolls on their respective cams, which latter are carried on the 95 shafts 77 and 78 as shown.

In front of the above described members there is mounted a bracket 110 carrying a lever 119, having a spring seated jaw 120 which is operated by its roll 122 coacting 100 with the eccentric 123 mounted on the shaft carrying the worm wheel 125, which is driven from the driving shaft 35 aforesaid through gear 37, gear 145 on shaft 128, pinion 129 and worm 126. 105

In order to progress the cigarettes from the table 39 I provide hands (see Fig. 4). These hands carry the cigarettes from the

shelf 47 upon which they are deposited from the table 39 by the carriers 41 and thence through the tipping mechanism and onto the belt 133. The hands 132 are mounted on a lever 134, pivoted to the upright rocking lever 135, which latter is pivoted at 136 and rocked by the connecting rod 137 from the crank disk 138. Another hand 139 is for the purpose of holding the cigarette while the tip is being made, and this hand is carried by a lever 140 pivoted at 141 to a suitable standard and rocked by the coaction of its roll 142 with cam 143 on shaft 144 driven from shaft 128 by gears 131 and 145. The crank disk 138 is also mounted on shaft 144 and carries a roll 146 for lifting the lever 134, whereby the hands 132 are given a motion similar to the carriers 41, but in the opposite direction.

The shafts 77, 78 and 79 are driven in unison from the driving shaft 35 by means of connections 80 as shown. The operation of the above parts will be clear from the following: The cigarette is placed upon the shelf 47 by the carriers 41 and is carried by the hands 132 until it is placed above the member 120 where the gummed cork to form the tip has been placed by any suitable means. Next the tip is formed by the combined actions of the two jaws 96 while the member 120 exerts a slight upward pressure and almost simultaneously with this the seaming member 150 descends and closes the lap on the cigarette, after which the hands 132 carry the finished cigarette away from the tipping mechanism and on to the conveyer 133 by means of which the finished product is finally removed from the machine.

Various modifications may be made without departing from the spirit of the invention.

Having described my invention, what I claim as new, and desire to secure by Letters Patent is:

1. In a cigarette tipping machine, the combination of a feeding mechanism comprising means for supplying cigarettes in a given position, hands for sliding said cigarettes from said given position into position to be wrapped, means for raising and moving said hands in the direction of said cigarettes including means for lowering said hands upon the cigarettes and returning same to their original position with said cigarettes, a jaw for holding each of said cigarettes in said position to be wrapped, wrapping means for closing the tip around the cigarette, a seaming member for closing the tip upon each cigarette, other hands for sliding the tipped cigarettes away from said seaming member and a discharge conveyer for removing same.

2. In a cigarette tipping machine, the combination of a feeding mechanism, hands and means for raising and moving said hands in the direction of the cigarettes as

they are fed into the machine including means for lowering said hands upon and returning same to their original position with said cigarettes, means for supporting each cigarette in position to be wrapped, wrapping jaws for folding the tip around the cigarette, a seaming member for closing the tip upon the cigarette and means for removing the tipped cigarettes.

3. In a cigarette tipping machine, the combination of a cigarette separating mechanism, a conveying mechanism for conveying the cigarettes singly into the machine, hands and means for raising and moving said hands in the direction of the conveyed cigarettes including means for lowering said hands upon and returning same to their original position with said cigarettes, a tipping mechanism for providing each cigarette with a tip, means for holding each cigarette in position to be tipped and means for removing the tipped cigarettes from the tipping mechanism.

4. In a cigarette tipping machine, the combination of a cigarette separator and conveyer, a table upon which said cigarettes are conveyed to a tipping mechanism, hands and means for raising and moving said hands over said table and in the direction of said conveyer including means for lowering said hands upon said cigarettes upon said table and returning said hands to their original position with said cigarettes to said tipping mechanism, and means for removing the tipped cigarettes.

5. In a cigarette tipping machine, the combination of a feeding mechanism comprising means for supplying cigarettes in a given position, hands for sliding said cigarettes from said given position into position to be wrapped, means for raising and moving said hands in the direction of said cigarettes including means for lowering said hands upon the cigarettes and returning same to their original position with said cigarettes, a jaw for holding each of said cigarettes in said position to be wrapped, wrapping means for closing the tip around the cigarette, said wrapping means comprising a pair of wrapping jaws being adapted to move upwardly and together upon the tip at the end of the cigarette, means for imparting a curvilinear motion to said jaws, a spring seated oscillating pad for supporting the cigarette upon which the tip is formed, and means for removing the tipped cigarettes.

6. In a cigarette tipping machine, the combination of a cigarette feeding device to feed the cigarettes singly upon a table, carriers mounted on either side of said table for lifting and moving the cigarettes along the same, hands and means for raising and moving said hands in the direction of said cigarettes including means for lowering said hands upon said cigarettes and returning

said hands to their original position with
said cigarettes into a position to be wrapped,
a tipping mechanism comprising jaws being
adapted to move upwardly and together
5 against the tip of the cigarette for providing
the cigarette with a tip, and means for re-
moving the tipped cigarettes.

In testimony whereof I affix my signature
in presence of two witnesses.
